(57) **CLAIM**

The ornamental design for a bottle, as shown and described.

DESCRIPTION

FIG. 1 is a front perspective view of a bottle showing the new design;

FIG. 2 is a front view thereof;

FIG. 3 is a right view thereof;

FIG. 4 is a top view thereof; and,

FIG. 5 is a bottom view thereof.

The dashed lines shown in the drawings are for illustrative purposes only and form no part of the claimed design. The dot-dash-dot lines shown in the drawings define the boundary of the claim and form no part of the claimed design.
